ATTORNEY

UNITED STATES PATENT OFFICE.

THOMAS W. STEWART, OF SOUTH SIOUX CITY, NEBRASKA.

HOG-SCRAPING KNIFE.

1,405,457.

Specification of Letters Patent.

Patented Feb. 7, 1922.

Application filed March 15, 1920. Serial No. 365,691.

To all whom it may concern:

Be it known that I, THOMAS W. STEWART, a citizen of the United States, and a resident of South Sioux City, in the county 5 of Dakota and State of Nebraska, have invented certain new and useful Improvements in Hog-Scraping Knives, of which the following is a specification.

In meat packing establishments, the hair 10 is removed from hogs by machines which fail to reach depressions of the critter, as the groins and other recessed parts. My present invention therefore has for its primary object the production of an improved 15 scraping device, particularly adapted to remove the hair from the critter, which the usual scraping machines fail to reach.

Furthermore, the invention contemplates a hog scraping knife, comparatively inexpensive in production, yet thoroughly efficient in operation.

The above and other objects and advantages I successfully attain in the embodiment hereinafter described, defined in the 25 appended claims and illustrated in the accompanying drawings, in which like characters of reference indicate corresponding parts throughout the several views, of which,—

30 Fig. 1 is a front elevation of one form of the device a portion thereof being cut away;

Fig. 2 is a plan thereof with a part cut away;

35 Fig. 3 is a front elevation of another form of the device, a part being cut away;

Fig. 4 is a plan thereof; and

Fig. 5 is an enlarged transverse section, taken on the line, 5—5 of Fig. 1.

40 While I have illustrated and hereinafter described the preferred embodiment of the invention, I would not be understood as being limited to such specific structures, for various alterations and modifications may 45 be made in the details of construction and arrangement of parts herein disclosed, without departing from the spirit and scope of the invention, as defined in the appended claims.

50 Referring now to the illustrations, the device consists essentially of an elongated curved blade, interposed between two elongated clamping plates, one of which serves as a guard to prevent laceration of the flesh

55 of the critter and a suitable handle for manipulating the device. The device presented

in Figs. 1 and 2, consists of a rear curved plate, 7, and two front plates, 8, hinged respectively to the ends of the parts, 7, as at 9, whereby the plates, 8, may be swung toward and from the rear plate. Between the parts 7 and 8, I interpose a blade 10, the concave edge of which 11 is sharp and extends a distance below the parts 8. The rear plate, 7, may be formed on its upper 65 edge with a forwardly extending flange, 12, which overlaps the edge of the blade and the parts, 8. The lower edge of the rear plate is provided with spaced guard teeth, 13, which depend a distance below the edge 70 of the blade to serve to prevent cutting of the body of the critter.

Suitable means are provided for removably clamping the blade between the plates, as short bolts, 14, which protrude through 75 the plates and transverse slots, 15, in the blade. To permit adjustment of the blade vertically winged nuts, 16, threaded upon the bolts when firmly screwed into engagement with the rear plate securely hold the parts against relative displacement, yet, by loosening the nuts on the bolts, it is clear the blade may be readily removed, sharpened and replaced. On the rear plate I secure a suitable handle, 16.

The above described embodiment is obviously intended for shaving or scraping convex surfaces on the body of the critter.

Referring now more particularly to Figs. 3 and 4, 18 represents the rear plate, 19 the front plate and 20 the blade. In this form the plates and blade are substantially semi-circular in shape and have their corresponding ends hinged together as at 21. The convex edge, 22, of the blade extends a distance 95 above the front plate and is in this form the sharp edge, while the rear plate is provided with spaced guard teeth, 23, which extend a distance above the blade. The blade is removably clamped between the plates as in the previously described form by bolts, 14, and winged nuts, 16, the blade being slotted as at 24 to receive the bolts and permit vertical adjustment of the blade. The rear plate carries the handle, 16. This 100 form it will be observed is intended for shaving the recessed parts of the critters.

Having thus described my invention what I claim as new and desire to secure by Letters Patent of the United States, is,—

1. A hog-scraping knife, including a crescent-shaped blade member, having a

sharp edge, a correspondingly-shaped plate member having guard teeth projecting beyond the sharp edge of the blade member, one of said members having bolt holes and 5 the other transverse slots, and clamping bolts passing through said holes and slots to secure the members together and permit their adjustment transversely of each other, to regulate the distance between the sharp 10 edge of the blade and the end of the guard teeth.

2. A hog-scraping knife, including an elongated blade having a curved sharp edge,

an elongated curved guard plate, against 15 which the blade rests, a handle on the plate, the plate being slotted vertically, and bolts passing through the blade and slots to secure the blade and plate together and permit vertical adjustment of the blade whereby the sharp edge of the blade may be moved toward and from the adjacent edge of the 20 guard plate.

In testimony whereof I have hereunto set my hand this 23rd day of February, 1920.

THOMAS W. STEWART.
